UNITED STATES PATENT OFFICE.

HARRY M. NAUGLE AND ARTHUR J. TOWNSEND, OF CANTON, OHIO, ASSIGNEES, BY
MESNE ASSIGNMENTS, TO THE AMERICAN ROLLING MILL COMPANY, OF MIDDLE-
TOWN, OHIO, A CORPORATION OF OHIO.

CONTINUOUS PICKLING APPARATUS.

Application filed December 19, 1924. Serial No. 757,030.

The invention relates to pickling tanks for removing oxidation and scale from wide steel strips and the like, while moving endwise continuously through a dilute solution of sulfuric acid or the like contained in the tank; and the object of the improvement is to reduce the length of such tanks and to improve the action of the pickling solution upon the metal.

10 The length of time required for pickling a wide strip of steel by passing it through a chemical solution, according to common practice, requires the use of a trough or tank for containing the solution, of such an extended 15 length as to render the same inconvenient and undesirable, if not prohibitive, within the ordinary bounds of a manufacturing plant.

This difficulty is overcome in the present improvement, by providing a rotatable drum 20 in each end of the tank over and around which the strip may travel to the under side thereof, and by providing a guide roll adjacent to the inner side of each drum for directing and holding the strip downward in the solution 25 while passing from one drum to the other.

The invention is illustrated in the accompanying drawings forming part hereof in which—

Figure 1 is a side elevation showing the improved pickling tank in longitudinal section, and apparatus which is preferably used in connection therewith;

Fig. 2, a plan view of the improved pickling tank; and

Fig. 3, a longitudinal section of the same on line 3—3, Fig. 2.

Similar numerals refer to similar parts throughout the drawings.

The apparatus may include a coil box A, a strip leveler B, a traveling spot welder C, a pickling tank D, a water washer E, conveyer rolls F, a double and shear G, and a strip coiler H, all arranged in series, as shown in Fig. 1 of the drawings.

45 The coil box A may be of any ordinary construction for holding a coil 10 of a strip 11 of steel or the like, and permitting the same to unwind for a continuous pickling operation; and the strip leveler B may include two 50 sets of rolls 12 of any well known construction and operation, for flattening the sheet and removing uneven fullness or buckles which may have been caused by reducing rolls

or other apparatus used in producing the strip.

55 The spot welder C may include a series of electrodes 13 mounted in a frame 14, supported on a carriage 14' provided with wheels 15, riding on a track 16, together with gripping devices 14'' on the front and rear sides of the frame, for clamping and holding successive strips with their ends overlapped in position between the electrodes for a spot welding operation, while the carriage is traveling forward on the track.

65 The pickling tank D may be made of wood or concrete 17 or other suitable material lined with an acid resisting metal 18 or other like material. The top of the tank may be open throughout its length and breadth and the same is made of sufficient length and breadth to contain a pickling solution 19 to accommodate a plurality of passes of the strip 11 in the manner described, as follows:

70 A rotatable drum 20 and 20' is mounted on a transverse axis in each end of the drum by means of bearings 21, which may be formed or secured on the side walls 17' of the tank. The drum 20' at the rear end of the tank is preferably located on a normal axis transverse the longitudinal axis of the tank, and the drum 20 at the forward end thereof is preferably located upon an axis extending at a slight angle from normal to the longitudinal axis of the tank, so that the strip 11 will 75 properly ride around the respective drums.

80 Each drum is preferably provided with a plurality of annular guide flanges 22 and 22' which divide the drum into a plurality of lateral sections for receiving successive passes of the strip as it rides around the drums, from one section of one drum to a corresponding section of the other drum, as illustrated in Fig. 2. The drums are preferably located with their lower sides well submerged in the 85 pickling solution contained in the tank so that the strip passing on the lower side of one drum to the lower side of the other drum will pass through the body of the solution.

85 Adjacent to the inner side of each drum is 100 mounted a guide roller 23 and 23', the same being mounted parallel to and cooperating with the corresponding drum and being supported by suitable bearings 24 on the side walls of the tank. The guide rolls 23 are so 105 positioned that their lower sides are also lo-

cated beneath the surface of the solution in the tank, and the passes of the strip from the upper side of the forward drum to the upper side of the rear drum are carried below the 5 guide rolls, which serve to direct and hold the strip immersed within the body of the solution.

The passes of the strip from the upper side of the forward drum 20' to the upper side 10 of the rear drum 20 form a series of coplanar passes. In a like manner, the passes of the strip from the lower side of the rear drum 20 to the lower side of the forward drum 20', form a similar series of coplanar passes. The 15 planes of these series of passes are parallel with each other. Furthermore the series of coplanar passes are held in close proximity with each other by means of the guide rolls 23 and 23', as well shown in Fig. 3.

20 A series of transverse skid rods 25 may be secured in the tank for separating the different or alternate series of passes of the strip moving to and fro within the tank; and it is evident that the movement of the passes in 25 reverse directions within the body of the solution, serves to agitate the same and cause new particles thereof to contact with the strip.

The water washer E may include strip supporting rolls 26 and transverse tubes 27 suitably apertured for spraying a cleaning water upon the strip to remove any acid or other coating which may be carried thereon from the pickling tank.

35 The conveyer rolls F may include two stands of power operating pinch rolls 28 arranged for drawing a strip through the apparatus and conveying it rearward to the double shear G; and between these rolls may be 40 provided transverse pipes 29 suitably apertured for hot air drying the trips.

The shear G is provided with shearing dies 30 on its front and rear sides and a shearing punch operating between the same for shearing the joint between two strips in front and in rear of their overlapped ends, so as to neatly disconnect them after the pickling and drying processes are completed.

45 The strip coiler H may be of any well known construction for winding the pickled strip 11' into a coil 10' and it is preferably provided with an independent motor 32 for this purpose.

50 In the operation of the apparatus a strip which has been flattened by the leveler B

and joined to another strip by the spot welder C, is moved continuously endwise over and around the drums in the ends of the pickling tank D, wherein the forward passes are directed and held downward in the solution by 60 the guide rolls; whence the strip is moved endwise through the water washer E by action of the conveyer rolls F, which moves the strip rearward through the double shear G, whereby successive strips may be severed by 65 cutting in front and in rear of the joints, whence the strips are wound by the strip coiler K.

By the improved apparatus the length of the pickling tank may be shortened in proportion to the number of passes made by the strip to and fro around the drums and under the guide rolls; and in making the passes in reverse directions, the movement of the strip 70 agitates the pickling solution so as to constantly bring the surface of the strip in contact with fresh particles thereof.

Furthermore, a less amount of pickling acid is required to fill the shorter tank, there is less difficulty in keeping the same tight and 80 the amount of depreciation and cost of maintenance are both reduced.

We claim:

1. Pickling apparatus for steel strips and the like, including a tank, a pickling solution in the tank, and drums at the ends of the tank for continuously passing the strip to and fro through the solution in the tank the axis of one of the drums being inclined from 85 normal to the longitudinal axis of the tank. 90

2. Pickling apparatus for steel strips and the like, including a tank, a pickling solution in the tank, and drums at the ends of the tank for continuously passing the strip to and fro through the solution in the tank 95 in substantially the same plane, and transverse skid rods in the tank for separating the alternate passes of the strip therein.

3. Pickling apparatus for steel strips and the like, including a tank, a pickling solution in the tank, a drum at each end of the tank for continuously passing the strip to and fro through the solution in the tank in a plurality of alternate passes over each drum and means in the tank for separating the alternate passes 100 of the strip therein.

105 In testimony that we claim the above, we have hereunto subscribed our names.

HARRY M. NAUGLE.
ARTHUR J. TOWNSEND.
